UNITED STATES PATENT OFFICE

GIOACCHINO GAMBACCINI, OF KENT, OHIO

CAR TRUCK

Application filed August 23, 1928. Serial No. 301,633.

This invention relates to trucks for railway cars, and has more particular reference to wear plates for the journaled boxes, journal box pedestals and equalizing bars of such trucks.

The primary object of the invention is to provide removable wear plates which may be readily attached to the journal box, journal box pedestal and equalizing bar, and by means of which these parts are effectively protected from wear, one by the other.

A more particular object is to provide wear plates of the above kind adapted to be so attached to the parts as to be effectively removable and retained in place, and which are of simple and durable construction.

Other objects will appear as the nature of the invention is better understood, and the same consists in the novel form, combination and arrangement of parts hereinafter more fully described, shown in the accompanying drawings and claimed.

In the drawings, wherein like reference characters indicate corresponding parts throughout the several views,

Figure 1 is an outer end elevational view of a journal box operatively associated with a car truck pedestal and equalizing bar, all equipped with wear plates in accordance with the present invention;

Figure 2 is a side elevational view looking toward the right of Figure 1;

Figure 3 is an inner end elevational view of the device shown in Figure 1;

Figure 4 is a vertical section on line 4-4 of Figure 3;

Figure 5 is a horizontal section on line 5-5 of Figure 3;

Figure 6 is an enlarged perspective view of the journal box removed and showing the present wear plate supplied thereto;

Figure 7 is an enlarged perspective view of the pedestal having the present wear plate supplied thereto;

Figure 8 is an inverted perspective view of the supporting end of the equalizing bar provided with a wear plate constructed in accordance with the present invention;

Figure 9 is an enlarged perspective view of a modified form of journal box wear plate,

employed for cooperation with the pedestal;

Figure 10 is an enlarged perspective view of the wear plate employed on each of the projecting ribs of the pedestal jaws as shown in Figure 7;

Figure 11 is a perspective view of a modified form of wear plate for the inner end of the journal box;

Figure 12 is a fragmentary inner end elevational view showing a still further modified form of wear plate applied to the inner end of the journal box; and

Figure 13 is a fragmentary view partly in side elevation and partly in section, of the construction shown in Figure 12.

Referring more in detail to the drawings, the journal box B is provided upon its sides with pairs of vertical parallel ribs 5 which form grooves or guideways for reception of the inwardly projecting vertical ribs 6 on the jaws 7 of the truck pedestal P. Wear plates are provided to fit in the vertical grooves of the journal box B, the same being of channel-shape and each having a web 8 and side flanges 9 at right angles thereto which bear against the inner faces of the ribs 5 and are secured to the latter by countersunk screws 10 in the form of the invention shown in Figures 1 to 6 inclusive.

However, the form of wear plates shown in Fig. 9 may be employed in lieu of the wear plates above described. The form of the invention shown in the last named figure is similar to that above described except that the side flanges 9 are not provided with screw openings for attachment to the ribs 5, but the web is formed at its ends with inwardly directed tongues 11 adapted to respectively flatly engage the top and bottom walls of the journal box B and to be fastened to the latter by means of suitable screws passing through the end perforations or openings 12 in the tongues 11.

Channel-shaped wear plates are also provided upon the inwardly projecting vertical ribs 6 of the pedestal jaws 7, each latter wear plate embodying a web 13 and side flanges 14 at right angles thereto which engage the sides of the ribs 6. In the form of the invention shown in Figures 1 to 7 in-

clusive, the wear plates for the pedestal ribs 6 are secured to the latter by means of countersunk screws 15 passing through the end of the web 13 and entering the ribs 6 as shown clearly in Figure 7. However, as shown in Fig. 10, the web 13 may be imperforate, and end openings 16 may be provided in the side flanges 14 for reception of screws adapted to enter the sides of the ribs 6 for securing the wear plates in place. Naturally, with the constructions of Figs. 9 and 10, any likelihood of loosening screws causing scoring of the bearing surfaces, is avoided.

15 The journal box B is provided on its top with the usual upstanding spaced parallel ribs 17 between which is adapted to be seated the supporting end 18 of the usual equalizing bar 19, a transverse retaining rib 20 being provided on the top wall of the journal box and connecting the ribs 17 for seating reception in a transverse groove 21 in the supporting end 18 of the equalizing bar 19, as is well known in the art. In accordance 20 with the present invention, a wear plate is provided on the top of the journal box B and fitted between the ribs 17, said wear plate embodying a generally channel-shaped member including a web 21^a having an upwardly pressed transverse portion 22^a intermediate its ends adapted to fit the rib 20 and provided with upstanding right angular side flanges 23 which are divided at the ends of the upwardly pressed portion 22 to 25 permit ready formation of the wear plate from sheet metal. This wear plate for the journal box is preferably secured in place by means of screws 24 passing through the side flanges 23 and entering the ribs 17.

40 The supporting end 18 of the equalizing bar 19 is provided with a somewhat similar form of wear plate including a web 21^a adapted to cover the under surface of the end 18 and having an intermediate upwardly pressed transverse portion 22^a adapted to fit within the groove 21, upturned side flanges 23^a being formed on the web 21^a to fit against the sides of the supporting end 18 of the equalizing bar as shown clearly in Figure 8. The 45 inner end of the web 21^a may be fastened to the equalizing bar by means of spaced screws 25, and an upturned flange 26 may be provided upon the outer end of the web 21^a so that screws 27 may be passed therethrough 50 into the outer end of the equalizing bar for securing purposes.

A wear plate is also provided upon the inner end of the journal box B for cooperation with the adjacent outer end of the hub of the 60 car wheel or the like, not shown, the latter wear plate including a web 28 adapted to flatly seat against the inner end wall of the journal box and having a central axle receiving opening as at 29, side flanges 30 being 65 provided on the web to engage the sides of the

journal box at the inner end of the latter as shown in the several views. As shown in Figures 3 and 6, the web 28 may be of generally rectangular form, while the side flanges 30 may not extend the full length of the web. 70 In this instance the wear plate is secured in place by means of screws 31 passing through the corner portions of the web 28 and entering the inner end of the journal box. However, as shown in Figs. 11 to 13 inclusive, the 75 web 28 may be of generally circular form to include the segmental portions 30^a which are turned at right angles to form the flanges for engagement with the sides of the journal box. These flanges 30^a are preferably apertured 80 as at 32 to facilitate attachment of the wear plates by means of screws 33. In the form of the invention shown in Figure 11, the web 28 is also provided with apertures 34 for further securing purposes, while in the form of 85 the invention shown in Figs. 12 and 13, the latter apertures 34 are omitted and the web 28 is provided at its top with a hook-shaped extension 35 adapted to engage over the top of the inner wall 36 of the usual vertical 90 guideway which accommodates the well known dust excluding slide or plate, the downturned free end or bill of this hook-shaped extension being tightly wedged in 95 place between the wall 35 and the usual closure strip 37 for the upper end of the guideway for the dust excluding slide or plate.

From the foregoing description it will be seen that I have provided a flanged wear plate for each of the various parts adapted to receive the wear incident to the relative movement between the journal box and pedestal and between the equalizing bar and the journal box, whereby, upon proper renewal of 100 the wear plate from time to time, said parts may be continued in use indefinitely because not directly receiving the wear and being capable of having new wear plates supplied thereto. Further, it is obvious that the wear plates can be inexpensively formed of metal of uniform thickness so as to be conveniently applied to the trucks of railway cars already in use.

110 Minor changes may be made without departing from the spirit and scope of the invention as claimed.

What I claim as new is:—

A journal box having a pair of spaced parallel upstanding ribs on its top and a 120 transverse rib connecting said pair of ribs, in combination with an equalizing bar having a supporting end adapted to seat upon the journal box between said pair of ribs and having a transverse groove to receive said transverse rib, and wear plates removably applied to one of said parts.

In testimony whereof I affix my signature.
GIOACCHINO GAMBACCINI.
